CLAIM

The ornamental design for a computer, as shown and described.

DESCRIPTION

FIG. 1.1 is a right side perspective view of a computer showing our new design;

FIG. 1.2 is a rear side perspective view thereof;

FIG. 1.3 is another rear side perspective view thereof;

FIG. 1.4 is a top perspective view thereof;

FIG. 1.5 is a left side perspective view thereof;

FIG. 1.6 is a front perspective view thereof; and

FIG. 1.7 is another left side perspective view thereof.

(Continued)

The dashed lines in the figures form no part of the claimed design. Surface shading in the figures is provided solely to indicate contour.

1 Claim, 7 Drawing Sheets
